UNITED STATES PATENT OFFICE.

EDWIN B. HAWKINS, OF SAN FRANCISCO, CALIFORNIA.

DIE-LIFTER.

SPECIFICATION forming part of Letters Patent No. 766,694, dated August 2, 1904.

Application filed October 28, 1903. Serial No. 178,942. (No model.)

To all whom it may concern:

Be it known that I, EDWIN B. HAWKINS, a citizen of the United States, residing at San Francisco, in the county of San Francisco and 5 State of California, have invented a new and useful Improvement in Die-Lifters, of which the following is a specification.

My invention relates to means for lifting a die from its mortar, thus avoiding the necessity of removing the die from the mortar by hand; and the object of the invention is to save time and labor in the handling of dies.

The device hereinafter described, and shown in the drawings, is also adapted for use in lifting pots of molten metal and in similar work, and I do not wish to limit its use to dies alone.

My invention consists of the novel features of construction and combination of parts hereinafter described, particularly pointed out in 20 the claims, and shown in the accompanying drawings, in which—

Figure 1 is an outline view, in side elevation, showing the manner of using my device. Fig. 2 is a perspective view of the lifter as in 25 use, a portion of the handle being broken off. Fig. 3 is a side elevation illustrating the handle at the angle required for releasing the die. Fig. 4 is a detail view showing the serrated inner end of the handle out of engagement 30 with the die. Fig. 5 is a similar view showing the inner end of the handle in engagement with the side of the die.

In the drawings, A represents a mortar of any suitable kind or any receptacle in which 35 a die or vessel may be placed. On an overhead track B travels a carriage B'. By means of the pulleys B², cable B³, and the hook B⁴ an object may be lifted above the floor and the carriage run to the place where it is desired to deposit the object, which can then be 40 lowered. This is a well-known construction and is shown to illustrate the practical use of my lifting device.

The device proper consists of a circular band 45 of metal C, having an undercut or beveled inner edge, as shown at C'. This band is cut and the ends turned outward, as shown at C², and

between these ends is pivoted the lower portion of a handle or lever D. This lever curves upwardly and outwardly and terminates in 50 the straight handle portion D'. At its lower inner end it is serrated or toothed, as shown at D². A metal loop or band E is arranged on the inner portion of the handle part adjacent the outer end of the curved portion and 55 nearer to the pivotal point than to the extreme outer end of the handle portion D'. A ring E' is secured in the loop and is adapted to be engaged by the hook B⁴.

In use the band C is slipped over the cylindrical die F, the handle being held in a raised position, throwing the lower serrated end out of engagement with the die. As soon as the band C has reached the proper position the handle is pressed downward, forcing the serrated portion D² of the lever into engagement 65 with the die. The handle is held in this position and the die lifted from the mortar and conveyed to the proper place by means of the pulleys, cable, and carriage, the pressure of 70 the serrated end of the lever preventing the die from slipping through the band, the die being held between this lower end of the lever and the upper inner sharp edge of the band, as shown in Fig. 3, and it will be noted 75 in this connection that the lever engages the die at a point below the band.

As before stated, this device can be used for lifting other objects than dies.

Having thus fully described my invention, 80 what I claim as new, and desire to secure by Letters Patent, is—

1. A device of the kind described comprising a metal band adapted to encircle a die, and a lever pivoted to said band and having a 85 lower serrated end adapted to engage the die at a point below the band.

2. A device of the kind described comprising a circular band, said band being cut and the ends turned outward, a lever having a 90 lower serrated end and an upper straight handle portion said lever being pivoted between the ends of the band at a point adjacent its lower end, means secured to the lever inter-

mediate its ends and adapted to lift same vertically, said means forming a fulcrum-point for the lever.

3. A device of the kind described comprising a metal band adapted to fit over a die, said band having an undercut inner face, and being cut transversely and the ends bent outward, a lever pivoted between said bent ends,

the pivotal point being adjacent the lower end of the lever, and means for lifting said lever vertically, substantially as described.

EDWIN B. HAWKINS.
